[57] ABSTRACT

In catheterization procedures using drainage tubing of uniform bore, the drainage of fluid is often in the form of a solid column of fluid which creates a vacuum in its wake, resulting in lesions in the bladder wall where wall tissue is drawn into the catheter drainage eyelet. This vacuum is greatly reduced if the drainage tube is provided with alternate zones of wide and narrow inside diameter wherein the wide zones are above the critical diameter which will support an unbroken column of fluid.

3 Claims, 3 Drawing Figures

FIG. 1

FIG. 2

FIG. 3

SURGICAL DRAINAGE TUBE

This application is a continuation-in-part of my copending application Serial No. 758,423, filed September 9, 1968 now abandoned.

This invention relates to drainage tubes used for transferring urine from a catheter to a drainage bag or storage vessel. More particularly it relates to a drainage tube of an improved design which discourages the formation of a solid column of urine in the lumen of the tube.

Recognition of the danger of introducing infectious organisms by urinary drainage systems which are open to the air has led to various modifications of a closed technique wherein a catheter has attached to its proximal portion a convenient length of clear plastic tubing which terminates in a so-called drip chamber attached to the side wall of a drainage bag. Efforts are made to prevent the entry of air into the drainage tubing and the catheter.

When fluid is drained from the body, however, it frequently fills the entire lumen of the drainage tube in a broken or unbroken column. The descent of such a column of fluid through the drainage tube by gravity flow creates a negative pressure or vacuum in the wake of the flow, and this vacuum is transmitted back through the catheter to the distal portion thereof. This frequently results in a portion of the bladder wall being drawn into the eyelet in the catheter tip, under suction, with consequent irritation or even the formation of a lesion subject to invasion by infectious organisms.

Recognition of this deficiency has led to various proposals for the introduction of filtered air into the system. Such devices, however, while effective, are intricate and expensive to manufacture. It is also known to provide drainage tubes which are provided with a multiplicity of inwardly and outwardly extending corrugations, for the purpose of preventing kinking of the tube. Such tubes are longitudinally extensible, and are made by an expensive mold-blowing process which limits their production to short pieces.

It is with improvements in such systems that the present invention is concerned. It is a primary objective of this invention to provide a drainage tube which will minimize the formation of a solid column of fluid descending by gravity through said tube. It is a further object of the invention to provide a drainage tube which will minimize the negative pressure formed in the normal operation of a catheter-drainage tube-drainage vessel system. It is an additional object of this invention to provide a drainage tube which minimizes the need for a drip tube fixed to a drainage bag.

The customary drainage tube used to conduct fluid from the proximal end of the catheter to the drainage vessel is a straight-walled flexible transparent plastic tubing, conventionally of about three-eighths inch outside diameter with walls about one thirty second of an inch thick. It has been found that if the normally uniform bore of a plastic drainage tube is converted to a bore or lumen having a periodically variable diameter with the maximum diameter of the lumen above the critical diameter of a tube which will support an unbroken column of fluid, the formation of a solid column or plug of descending fluid is minimized or even eliminated, with consequent reduction in the air aspirated downwardly through the system and a reduction in the vacuum created in the wake of the advanc-

ing fluid. Also a considerable increase in the lateral flexibility and manipulability of the tube is achieved, compared with a tube of uniform diameter at or above the critical diameter, the term critical diameter here referring to the maximum diameter above which a given tube will no longer support an unbroken column of a given volume of fluid. The tube is resistant to longitudinal extension, and has the further advantage of being extrudable in continuous lengths, providing an economy of manufacture which makes their one-time use feasible.

The invention will be more clearly understood with reference to the following description and drawings, in which:

15 FIG. 1 represents a preferred embodiment of the invention, partially broken away, and enlarged.

FIG. 2 represents a test method for measuring the vacuum-inducing potential of a drainage tube.

20 FIG. 3 represents, partly broken away, the drainage tube of this invention attached to a conventional urinary catheter at the distal end and terminating in a conventional urine collection bag at its proximal end.

25 Referring to FIG. 1, a segment of a drainage tube 10 is shown, fitted with a conventional adapter 12 for insertion into catheters of varying sizes. The side walls of the drainage tube are not straight and of uniform diameter, but are convoluted into a spaced-apart series of straight-walled sections 18 each separated from the 30 succeeding straight-walled section by a bulbous enlargement 19, which may be substantially spherical or oval-shaped. The tube is thus divided into a set of alternating straight-walled chambers of minimum diameter 16 and curved-walled chambers of maximum diameter 14. Such a formation, it has been found, is conducive to 35 breaking up the tendency of draining fluid to form a cylindrical plug or broken series of plugs reaching from inner wall to inner wall, as in conventional smooth bore tubing.

40 In the employment of conventional smooth-bore drainage tubes, the passage of fluid through the tube has been found to create vacuum readings as high as 60 millimeters of mercury, the average vacuum being 30 to 40 millimeters in the lengths of tubing conventionally employed to span the distance from catheter to collection bag. It is desirable that such a vacuum be reduced by 50 percent or more, preferably to a level of 15-20 millimeters of mercury or less.

45 For this purpose, it is desirable that the length of the bulbous section be no less than the length of the straight-walled section (Y and X of FIG. 1, respectively). Expressed differently, in the drainage tubes of this invention the summation of the lengths of the straight-walled segments of the tube should not exceed 50 percent of the total length of the tube. In FIG. 1, the length 50 Y of the bulbous portions is approximately four times the length X of the straight-walled sections, so that the summation of straight-walled sections constitutes 20 percent of the total length of the tube.

55 To test the efficiency of a tube of this design, the test depicted in FIG. 2 was employed. A conventional smooth-bore drainage tube 20 was connected by a sidearm 22 to a vacuum recording device 24 such as a mercury manometer. When a quantity of fluid was 60 poured into the upper end of the tube 20 and allowed to flow through the tube by gravity, vacuum readings of

around 50 millimeters of mercury were developed in the manometer. When the smooth-bore tube 20 was replaced by the variable bore tube of FIG. 1, repetition of the test gave vacuum readings of 20 millimeters of mercury or less, or an average reduction of 60 percent in the strength of the vacuum developed in the wake of the descending fluid.

In general, it has been found that drainage tubes of this invention function optimally when the inside diameter of the tube tube at its enlarged or widest point 10 is at least 0.250 inches, and when this diameter is at least 25 percent greater than the minimum inside diameter of the tube. In such constructions, substantial reduction of 50 percent or more in the vacuum developed during drainage may be achieved. To some extent this will depend on the frequency and the sharpness of the changes in diameter of the lumen of the tube, but in general it is preferred that for simplicity in manufacture the lumen of the tube have a diameter in selected regions which is between 25 percent and 100 percent greater than the diameter in selected other regions.

It is customary in closed catheterization systems to provide a so-called "drip chamber," customarily attached to the wall of the collection bag. Its function is 25 to provide a break in the continuous stream of urine, thus discouraging the retrograde growth of bacteria. Drainage tubes of this invention, by providing what may be considered as a series of drip chambers within

the tube itself, minimize or obviate the need for conventional drip chambers attached to the collection bag.

Having thus described my invention, I claim:

5 1. In a drainage system for the catheterized drainage of urine by gravity flow, comprising a urinary catheter and a urine collection vessel, that improvement which comprises

a laterally flexible length of plastic tubing attached to the proximal end of said catheter

the walls of said plastic tubing comprising a set of axially spaced-apart straight-walled sections, said straight-walled sections alternating with sections in which the walls of said plastic tubing are expanded in bulbous form,

the lumen of said plastic tubing thereby varying in diameter along its length,

and the proximal end of said plastic tubing terminating in said urine collection vessel.

2. The system according to claim 1 in which the summation of the lengths of the straight-walled segments does not exceed 50 percent of the total length of the tube.

3. The system according to claim 1 wherein the maximum inside diameter of the plastic tubing is between 25 percent and 100 percent greater than the minimum inside diameter of said tubing, said maximum inside diameter being at least 0.250 inches.
